UNITED STATES PATENT OFFICE.

MARTIN PAULSON, OF MISSOURI VALLEY, IOWA.

DESIGN FOR A WHEEL-CLAMPING FOOT FOR LIFTING-JACKS.

SPECIFICATION forming part of Design No. 33,376, dated October 16, 1900.

Application filed September 22, 1900. Serial No. 30,861. Term of patent 7 years.

To all whom it may concern:

Be it known that I, MARTIN PAULSON, a citizen of the United States, residing at Missouri Valley, in the county of Harrison and State 5 of Iowa, have invented and produced a new and original Design for a Wheel-Clamping Foot for Lifting-Jacks, of which the following is a specification.

This invention relates to a new and original 10 design for a wheel-clamping foot for lifting-jacks, and has for its object to provide a design of this character which shall be both useful and ornamental.

The leading feature of the design resides 15 in a rectangular base-block provided at one end with an offstanding arm extension arranged at an obtuse angle to the base-block, said arm extension having a spur projecting from the upper end thereof and from the side 20 opposite to the base-block.

A minor feature of the design is the base-block having the arm extension and the spur projecting from said extension and tapering toward its outer end, said spur also having 25 its under face inclined downwardly from the arm extension.

In the drawings, Figure 1 is a perspective view of a wheel-clamping foot for lifting-jacks embodying the herein-described design. Fig. 2 is a top plan view thereof. Fig. 3 is a 30 side elevation of the same.

Referring particularly to the drawings, the numeral 10 designates the base-block, which is rectangular and is provided at one end with the offset arm extension 11. This arm 35 extension is arranged at an obtuse angle to the base-block and has at its upper end a spur 12, that projects from the side opposite to the base-block 10. The spur 12 tapers toward its outer end, and the under face 13 inclines downwardly from the arm extension 11. 40

What is claimed is—

The design for the wheel-clamping foot for lifting-jacks herein shown and described.

In testimony that I claim the foregoing as 45 my own I have hereto affixed my signature in the presence of two witnesses.

MARTIN PAULSON.
